ATTORNEY

UNITED STATES PATENT OFFICE.

WILLIAM E. HAWKINS, JR., OF PELHAM, NEW YORK.

WRENCH.

1,424,643.

Specification of Letters Patent. Patented Aug. 1, 1922.

Application filed June 7, 1921. Serial No. 475,630.

To all whom it may concern:

Be it known that I, WILLIAM E. HAWKINS, Jr., a citizen of the United States, and a resident of Pelham, in the county of Westchester and State of New York, have invented new and Improved Wrenches, of which the following is a specification.

My invention relates to the class of devices above named, and an object of my invention, among others, is to provide a wrench of this class that shall be extremely simple and durable in construction and particularly efficient in operation.

One form of wrench embodying my invention, and in the construction and use of which the objects herein set out, as well as others, may be attained, is illustrated in the accompanying drawings, in which—

Figure 1 is a side view of my improved wrench showing the jaws in position to grasp an object.

Figure 2 is a similar view but showing the jaws in open position.

Figure 3 is a perspective view of the wrench.

In the accompanying drawings the numeral 5 indicates a shank having a fixed jaw 9 rigidly secured thereto at one end and in a manner common to wrenches of this kind, the opposite and extreme end of the shank being formed into a handle 7, said parts in fact comprising a fixed jaw with a supporting extension therefrom. The inner edge of the shank is formed with serrations 8 beginning a short distance from the jaw 6 and extending along the shank toward the handle 7, the edge thus formed comprising a holder edge on said shank. The movable jaw 9 is supported by and at the end of a lever handle 10, this jaw 9 being so disposed that when said lever handle is in its closed position, as shown in Figure 1, the working face of the jaw 9 will be substantially parallel with the working face of the fixed jaw 6. A detent 11 projects from the back of the lever handle 10 in proximity to the jaw 9, this detent being arranged to engage the teeth or serrations 8 to retain the jaw 9 in fixed positions with respect to the jaw 6.

As a means for supporting the jaw 9 and the lever handle 10 I provide a jaw carrier 12 of U-shape and that is formed to extend around the outer edge and on opposite sides of the shank 5 and handle 7, this carrier being open on what may be termed its front

edge, and within this opening the jaw 9 is pivotally secured as by means of a pivot 13 extending through the side parts of the carrier.

The fixed jaw and its attached handle and shank and the movable jaw with its lever handle are both punched or cut from metal in a manner that will be readily understood, and for which reason the fixed and pivoted jaw members together with their handles are preferably formed from metal of the same thickness, this formation of said members of uniform thickness also simplifying the formation of the jaw carrier 12 in that it is necessary only to bend it at the back, and, if desired, it may be cut away as shown in the drawings. The ends of these handles may be formed into screw drivers of different sizes, and as illustrated in the drawings.

The detent 11 may be formed in any suitable manner, a satisfactory construction embodying that in which the detent is separately formed and thereafter attached to the jaw as shown in the drawings.

When thus constructed this detent may be hardened thereby enabling it to withstand the wear incident to its use.

The construction is such that the jaw members may be constructed at a minimum cost; the formation of the carrier is extremely simple and inexpensive; and the assembling of the device is so simple as to require little consideration as to expense of manufacture.

In accordance with the provisions of the patent statutes I have described the principles of operation of my invention, together with the device which I now consider to represent the best embodiment thereof; but I desire to have it understood that the device shown is only illustrative and that the invention may be carried out by other means.

I claim—

1. A wrench comprising a fixed jaw member including a jaw projecting from its front edge and a supporting extension therefrom having a holder edge, a carrier of U-shape open at its front edge to receive said extension and to slide thereon, a movable member pivotally mounted between the side parts of said carrier at the front edge of the fixed jaw member and including a movable jaw and a handle rigidly secured thereto to effect pivotal action thereof, said handle projecting from said jaw substan-

- tially parallel with the other handle in the grasping position of the jaws, and a detent upon said movable member adapted to engage said holder edge.
5. A wrench comprising a fixed jaw member including a jaw projecting from its front edge and a supporting extension therefrom having a holder edge, a movable member comprising a handle and a jaw rigidly secured thereto, said jaw members with the handle extensions being formed of substantially the same thickness, a carrier formed of comparatively thin metal wrapped about the extension from the fixed jaw member 10 and open at one edge to receive and pivotally support said movable member, and a detent upon the movable member adapted to engage said holder edge.
3. A wrench comprising a fixed jaw member with a supporting extension therefrom having a holder edge, a carrier formed to U-shape from sheet metal with substantially parallel branches, said carrier being slidably mounted upon said extension with the bend 15 thereof at the back of said extension, said extension being received within the open edge of said carrier, a movable member pivotally mounted within the open edge of said carrier and comprising a jaw and a handle extending substantially parallel with
- said supporting extension when the jaws are in their grasping position, and a detent projecting from the back edge of said movable member to engage said holder edge.
4. A wrench comprising a fixed jaw member including a jaw and a supporting extension therefrom having a holder edge, a carrier of U-shape open at its front edge to receive said extension and to slide thereon, a movable member pivotally mounted between the side parts of said carrier and comprising a jaw and a handle rigidly secured thereto, and a detent formed from a separate piece of metal and rigidly secured to said movable member to engage said holder edge.
5. A wrench comprising a fixed jaw member including a jaw projecting from its front edge and a supporting extension therefrom having a holder edge, a carrier of U-shape closed at its back edge and open at its front edge to receive said extension and to slide thereon, and a movable member received within the open edge of said U-shaped jaw carrier and pivotally mounted between its side parts, said movable member including a handle and a detent to engage the edge of said supporting extension.

June 1, 1921.

WILLIAM E. HAWKINS, JR.
